UNITED STATES PATENT OFFICE.

DOMENICO PALLARIA, OF LONDON, ONTARIO, CANADA.

SAFETY ATTACHMENT FOR AEROPLANES.

Application filed November 5, 1927. Serial No. 231,261.

This invention relates to aeroplanes particularly intended for long distance flights over the water and which are not provided with permanent floats or boat-like bodies, and my object is to devise means for quickly increasing the buoyancy of the aeroplane, in case of a forced descent over water, to an extent sufficient to support both aeroplane and crew.

I attain my object by locating within a normal part of the structure a frame which may be extended in case of need outside the structure, and which carries an inflatable air bag, and by providing means whereby the air bag when so projected may be inflated. Preferably such a safety device is located in each wing tip of a monoplane or in the lower wing tips of a bi-plane.

The invention is hereinafter more fully described and is illustrated in the accompanying drawings in which

Fig. 1 is a plan view, partly broken away, and more or less diagrammatic, of a monoplane provided with my safety attachment;

Fig. 2 a front elevation of part of the same; and

Fig. 3 a detail of the operating mechanism.

In the drawings like numerals of reference indicate corresponding parts in the different figures.

The drawings show a monoplane of known type and require no description in detail.

Within each wing tip of the plane there is provided a chamber 1. In each chamber is fitted a frame 2 adapted to slide on the guides 3 so that it may be projected from the chamber as indicated in dotted lines. Suitably secured in each frame is an air bag 4 made of any suitable water-proof and air-tight material and of suitable size to be contained within the wing tip when the frame 2 is retracted. Means are provided for inflating these bags when the slides are projected. In Fig. 2 one of these air bags is shown in its inflated condition.

While any suitable means will be provided for extending and retracting the frames 2, I prefer to so arrange the mechanism that the frames will be automatically extended on the release of latches controlled by the pilot.

Each frame 2, it will be noted, has a nut 5 connected therewith through which passes a screw 6 preferably of a steep pitch. Each

screw is mounted for rotational movement while held from lengthwise movement. Within the body of the plane is journalled the gear wheel 7, with which mesh the pinions 8 on the screws 6. This gear wheel is connected with a shaft 9 provided with a crank 10 so that it may be operated by the pilot to actuate the screws to retract the frames 2. Springs 11 are provided tending to extend the frames. Preferably these springs are coil springs surrounding the screws 6 and bearing against the nuts 5 and the inner bearings of the screws 6. Latches 12 are provided pivoted on the wings of the plane and adapted to engage keepers 22 formed in the frames 2. These latches are formed as bell crank levers and are actuated by means of cables 13 connected with opposite ends of a lever 14 fulcrumed in the body of the plane in a suitable position to be actuated by the pilot.

To supply air for inflating the air bags I preferably employ two cylinders 15 containing compressed air and preferably detachably secured to the framework of the plane. Connected with each air cylinder is a pipe 16 provided with a valve 17 governing the admission of air to the flexible pipes 18 connected with the air bags. The valve stems are provided with levers 19 connected by cables 20 to opposite sides of a drum 21 mounted in the body of the machine and suitably positioned for operation by the pilot. The air bags may thus be simultaneously inflated after the frames carrying them have been projected as described.

From the constructions described it will be evident that in case of a forced descent the buoyancy of a plane can be almost instantly increased to an extent sufficient to float the machine and its crew, and that the extra buoyancy is located where it would be most effective in keeping the body of the plane on an even keel and with the crew well above the surface of the water.

What I claim as my invention is:

1. An aeroplane provided with a chamber; a slide adapted to be projected from said chamber; an inflatable air bag carried by said slide and normally contained within the chamber; and means for inflating the bag after the slide has been projected and the bag thus carried outside the said chamber.

2. An aeroplane provided with chambers

in its wing tips open at their outer ends; tracted expandible air bags, normally shielded from external air pressure; means for projecting the bags from the chambers, and means for expanding said bags to serve as floats when thus projected.

5 inflating the bags when the slides are projected.

3. An aeroplane having its wing tips provided with chambers and with normally con-
